UNITED STATES PATENT OFFICE.

WALTER S. MINOR, OF CUNNINGHAM, TENNESSEE.

ROTARY ENGINE.

No. 920,976.

Specification of Letters Patent.

Patented May 11, 1909.

Application filed November 14, 1908. Serial No. 462,649.

To all whom it may concern:

Be it known that I, WALTER S. MINOR, a citizen of the United States, residing at Cunningham, in the county of Montgomery and 5 State of Tennessee, have invented certain new and useful Improvements in Rotary Engines, of which the following is a specification, reference being had to the accompanying drawings.

10 This invention relates to improvements in rotary engines and more particularly the one set forth in Patent No. 900,410 granted to me on October 6, 1908.

The object of the present invention is to 15 improve and simplify the construction and operation of rotary engines of this character and to render the same less expensive and more durable in construction, lighter running and more economical in use, self lubricating 20 and also reversible.

With the above and other objects in view, the invention consists of the novel features of construction and the combination and arrangement of parts hereinafter fully described and claimed, and illustrated in the 25 accompanying drawings, in which—

Figure 1 is a vertical transverse section through the improved rotary engine; Fig. 2 is a vertical longitudinal section; Fig. 3 is an 30 elevation of the inner face of one of the removable end plates or heads of the body of the cylinder; Fig. 4 is an enlarged sectional view showing the roller and roller bearing for one of the guiding pins of the piston blades; 35 Fig. 5 is a detail view of one of the packing plates arranged upon the pins of the piston blades; and Fig. 6 is a detail section taken on the plane indicated by the line 6—6 in Fig. 4.

40 My improved reversible rotary steam engine comprises a cylinder 1 having its open ends covered by removable heads 2 which are secured by bolts 3, annular ribs being provided upon the inner faces of the heads 2 to 45 enter annular grooves in the ends of the cylinder to properly center the head and provide an effective connection, as shown in Fig.

2. At the top of the bore of the cylinder is formed a longitudinally extending rib which 50 provides an abutment 4 and in an enlargement upon the exterior of the top of the cylinder are formed two similar passages 5, 6 either of which may serve as a steam inlet while the other serves as a steam exhaust.

55 A slideable cup valve 7 is arranged in a valve chamber or steam chest 8 for the purpose of

reversing the inlet and exhaust of steam to the engine and thereby reversing the engine, as presently explained. Said valve 7 is adapted to bring either of the passages 5, 6 60 into communication with an exhaust passage 9 which may in turn have a suitable exhaust pipe connected to it. A suitable steam inlet pipe is adapted to be connected to an inlet connection 10 arranged at the top of 65 the steam chest 8; and in one side or end of said chest is a stuffing box for a slideable operating rod 11 of the valve 7, which rod may be connected to a lever or other operating device. The bottom of the exterior of 70 the cylinder 1 is shaped to provide suitable supporting and attaching feet 12 and in the center of said bottom is a drain passage 13 which is adapted to permit the water of condensation to be drawn out of the cylinder 75 and which is controlled by a pet cock 14 or the like. To facilitate the outlet of steam from either side of the cylinder according to the direction of rotation of the piston within the same, the inner face of the bore of the 80 cylinder is cut away, as shown at 15, from the passages 5, 6 to points approximately midway the sides of the cylinder, the lower extremities of said cut away or enlarged portions 15 being beveled, as indicated at 16, 85 for a purpose presently explained.

17 denotes a shaft extending concentrically through the cylinder and journaled in bearings 18 on the cylinder heads 2, said bearings having composition metal boxes 19, oil 90 supply passages 20, and stuffing boxes 21, as clearly shown in Fig. 2. Fixed to said shaft 17 is a concentric cylinder piston 22 carrying two radially slideable piston blades 23 arranged at diametrically opposite points 95 in longitudinal recesses or slots 24 formed in the piston. The piston 22 is of less diameter than the bore of the cylinder so as to provide an annular space within the latter for the passage of steam, which space is to 100 be intercepted by the piston blades 23. Upon the ends of the piston are secured removable heads 25 in the form of circular plates which are of the same diameter as the bore of the cylinder and are provided around 105 their edges or peripheries with suitable packing strips 26, the latter being set in grooves in said edges of the piston heads and oil being supplied to them through passages 26^a, as shown in Fig. 2. In the piston heads or 110 plates 25 are formed radial slots 27 adapted to receive guide pins 28 formed at opposite

points upon the ends of the piston blades 23. The latter are rectangular in shape and have their outer edges grooved longitudinally to receive packing strips 29 which are projected by coil springs 30 against the inner wall or bore of the cylinder and also against the bottoms of the enlargements 15 of said bore, the inclined ends 16 of said enlargements 15 being provided for the purpose of guiding the 10 packing strips 29, as will be readily understood. The inner edges of the piston blades 23 are formed with central recesses 31 to slide against the inner faces of the piston heads 25 and into and out of recesses 32 15 formed in the bottoms of the recesses or slots 24 of the piston, as clearly shown in Fig. 2 of the drawings.

The piston blades 23 are moved into and out of the piston by the passage of the guide pins 28 through endless guide grooves 33 formed in the inner faces of the cylinder heads 2 and having concentric portions 34 and eccentric or cam portions 35, as clearly shown in Fig. 3, and in order to reduce friction and to cause the blades to work easily, anti-friction rollers 36 are arranged upon the pins 28 to travel in the grooves 33. To further reduce friction anti-friction roller bearings 37, shown in Figs. 4 and 6 of the drawings, 20 are arranged within the rollers 33 and upon reduced cylindrical portions 38 formed on the pins 28, which latter are square or of rectangular shape in cross section. While the roller bearings 37 may be of any suitable 25 form and construction they are preferably composed of cylindrical rollers having pivots arranged in a cage consisting of annular rings 39 connected by rods 40, and said bearings are retained on the cylindrical portions 38 of the pins 28 by the engagement of the inner rings 39 with shoulders 41 formed by reducing the pins 28 and also by washers 42 held on reduced screw threaded extremities 43 of said pins by nuts 44, as clearly shown 40 in Fig. 4 of the drawings. To supply lubricant to the roller bearings, radial oil passages 45 are formed at four or more points in the rollers 38 and are adapted to receive oil or lubricant from inclined oil passages 46 45 formed in the heads 2 at the upper top portions of the grooves 33. Suitable oil cups may be applied to the outer ends of the oil passages 46 to constantly supply lubricant to the same.

In order to prevent steam from working around the ends of the piston blades 23 and into annular recesses or cavities 47 formed in the inner faces of the cylinder heads 2, packing plates 48 are arranged upon the 50 squared or flat faced portions of the pins 28 upon the outer faces of the piston heads 25. One of these plates 48 is shown in Fig. 5, upon reference to which it will be seen that it has a square central opening to receive 55 the pin 28 so that it cannot rotate upon the

latter; and upon reference to Fig. 2 it will be seen that said plates are of sufficient length to cover the slots 27 without regard to the positions of the pins 28 in said slots. However, to permit any steam to escape 70 from the recesses 47 that may work into the same and also to permit the water of condensation to drain from said recesses, downwardly inclined outlet passages 49 are formed in the cylinder heads 2 at the bottom portions of said recesses, as shown in Fig. 2.

In order to avoid compression in the slots or recesses 24 for the piston blades, without making said slots or recesses unduly wide, a 80 steam passage is formed in the piston around each of the piston blades, such passage consisting of two portions 50 on opposite sides of the slot 24 and connecting portions 51 which afford communication between the inner ends of the portions 50 and an enlarged portion or recess 52 which is in turn in communication with the bottom of the slot 24 and serves as a cage for a ball check valve 53. The latter is retained in 85 the recess 52 by a pin 54 and it is adapted to seat against either of the passages 51 according to the pressure of steam in said passages.

The abutment 4 is provided with a T-shaped packing strip 55, the cross portion of which is disposed outside of said abutment and has beveled edges 56 to guide the piston blades 23 and their packing strips 29; and a third portion or arm 57 of said T-shaped 100 packing strip 55 is slidable in a longitudinal groove formed in the abutment and is actuated outwardly by coil springs 58, as clearly shown in Figs. 1 and 2 of the drawings.

The operation is as follows: Assuming 105 the parts to be in the position shown in Fig. 1, the steam entering the chest 8 through the inlet 10 will pass over the valve through the passage 5 and into the left side of the cylinder and its pressure against the left blade 23 will cause the piston and its shaft to rotate in the direction indicated by the arrow in Fig. 1. The steam also seats the check valve 53 of the left piston blade to prevent the passage 110 of steam around said blade but at the same time to equalize pressure in the recess or slot 24 of such blade and prevent compression as the blade recedes into the piston upon the passage of its guide pins 28 through the cam portions 35 of the grooves 33. As the piston 115 22 rotates the tight blade 23 in Fig. 1 will be retracted into the piston owing to the movement of its guide pins 28 through the cam portions 35 of the grooves 33 and when the outer edge, or the packing strip in said edge, 120 leaves the wall of the cylinder bore the steam confined in the bottom portion of the cylinder between the two blades will pass out of the right side of the cylinder through the passage 6, then through the valve 7 to the outlet 130

9. When it is desired to reverse the engine the valve 7 is shifted to the left to cause its chamber to afford communication between the passages 5, 9 while the passage 6 is uncovered by it. When the valve is in a central or intermediate position steam will be cut off from both of the passages 5, 6 and both of the latter will be, to a slight extent, in communication with the outlet passage 9.
10. Having thus described the invention what is claimed is:
1. In a rotary engine, the combination of a cylinder having an abutment and steam passages on opposite sides of the abutment, cylinder heads provided with grooves having concentric and eccentric portions, a rotary piston, a radially slideable piston blade in said piston provided at its ends with guide pins to travel through the grooves in the cylinder heads, said pins having reduced cylindrical portions and reduced threaded extremities, anti-friction rollers arranged upon said pins and adapted to travel through the grooves in the cylinder heads, roller bearings arranged on the reduced cylindrical portions of the pins and within the anti-friction rollers, said roller bearings having their cages engaged with the shoulders formed by the reduced cylindrical portions of the pins, washers arranged on the reduced threaded extremities of said pins and engaged with said anti-friction rollers and nuts upon said reduced threaded extremities of the pins.
  2. In a rotary engine, the combination of a cylinder having an abutment and steam passages on opposite sides of the abutment, cylinder heads provided with grooves having concentric and eccentric portions, a rotary piston, a radially slideable piston blade in said
- piston provided at its ends with guide pins to travel through the grooves in the cylinder heads, said pins having squared flat faced portions and cylindrical portions, rollers upon the cylindrical portions of the pins and adapted to travel in the grooves in the cylinder heads, piston heads upon the ends of the piston and formed with radial slots to receive the flat faced portions of the pins of the piston blade, and packing plates apertured to receive the flat faced portions of said pins and adapted to engage the outer faces of the piston heads to close the slots in said heads.
3. In a rotary engine, the combination of a cylinder having an abutment and steam passages on opposite sides of the abutment, cylinder heads formed in their inner faces with grooves having concentric and eccentric portions, said cylinder heads being also formed with oil passages in communication with the upper portions of their grooves, a rotary piston, a radially slideable piston blade in the piston and provided at its ends with guide pins to travel through the grooves in the cylinder heads, anti-friction rollers upon said guide pins and formed with oil passages extending from their peripheries to their bores and adapted to receive oil from the oil passages in the cylinder heads and to convey the same to said pins, and anti-friction bearings arranged within said rollers and upon said pins and supplied with oil through the passages in said rollers.

In testimony whereof I hereunto affix my signature in the presence of two witnesses.
